UNITED STATES PATENT OFFICE.

KARL M. MACILVAINE, OF NEW YORK, N. Y., ASSIGNOR TO RADIO CORPORATION OF AMERICA, A CORPORATION OF DELAWARE.

VACUUM-TUBE CIRCUITS.

Application filed May 6, 1924. Serial No. 711,377.

This invention relates to new and useful improvements in vacuum tube circuits, more particularly, to the supply circuits for heating the cathodes of vacuum tubes.

5 It is an object of this invention to provide a new and improved arrangement whereby the necessity for adjustable rheostats in vacuum tube circuits is avoided.

10 It is a further object of this invention to provide means whereby any desired number of vacuum tubes may be lighted at the proper temperature without the adjustment of rheostats.

15 It is another object of my invention to provide an arrangement adaptable to radio receivers embodying a number of tubes in cascade whereby the operator may insert the telephone plug in the jack desired and all tubes necessary to operation will be lighted 20 and at the proper temperature.

Other and ancillary objects will be apparent from the specification.

The novel features which I believe to be characteristic of my invention are set forth 25 with particularity in the appended claims; the invention itself however, both as to particular embodiments thereof and mode of operation, will best be understood by reference to the following description taken in 30 connection with the accompanying drawing, in which the single figure shows a circuit embodying my invention.

With the so-called "thoriated filament" tubes now in general use, it is important that 35 the filament temperature be not allowed to exceed a certain value. As these tubes are widely used as amplifiers in radio receiving apparatus, they are subject to operation quite frequently by persons unskilled in their 40 use and such persons frequently burn the tubes at much higher than their rated voltage, which materially shortens the life of the tubes. The arrangement which I have shown makes it possible to utilize such tubes 45 without danger of their being burned at excessive voltages by anyone, and where my invention is applied to radio receivers, it makes possible the simplification of the receiver by eliminating the necessity for rheostat knobs on the panel or elsewhere. Since 50 the proper value of resistance to maintain normal filament voltage on the filaments is taken care of by my arrangement quite automatically and independently of any care 55 on the part of the operator, it is evident

that my invention is of particular usefulness in radio apparatus built for broadcast listeners.

Referring more particularly to the drawing, T_1 , T_2 and T_3 designate the usual form 60 of vacuum tubes having filament F, grid G and plate P.

Since my invention relates particularly to the control of the filaments, the grid and plate circuits of the tubes have not been completed, but it will be evident that any suitable arrangement may be used. For instance, T_1 may represent a detector tube, T_2 the first audio frequency amplifier and T_3 a second audio frequency amplifier. 70

If the tubes are so arranged it may be advisable under some conditions to use no audio frequency amplification, connecting the telephones in the output of the tube T_1 . Under other conditions, it may be advisable to connect the telephones in the output circuit of either tubes, T_2 or T_3 . In order to avoid unnecessary use of the tubes, I have provided automatic filament control jacks, J_1 , J_2 and J_3 , jack J_1 being associated with 80 tube T_1 , J_2 with T_2 and J_3 with T_3 . As shown, jacks J_1 and J_2 are standard seven-spring jacks; whereas, J_3 is a standard four-spring jack. It will be understood that 85 transformers or other suitable coupling means are interconnected with the jacks in the usual manner so that by inserting the telephone plug in jack J_3 all tubes are functioning, being coupled in cascade by transformers or other suitable coupling. When 90 the telephone plug is inserted in jack J_2 the transformer or other means coupling tube T_2 to tube T_3 is cut out and the telephones are inserted in its place. A similar 95 result is obtained by the insertion of the telephone plug in jack J_1 .

The filaments of all tubes are energized 100 from battery B. Connected between the positive terminal of battery B and the spring of jack J_1 I provide a resistance R of any suitable kind, such as wire, carbon, etc., as shown. From an intermediate point on this resistance R a lead is carried to spring 1 of jack J_2 and from a point 6 between this intermediate point 5 and the end of resistance 105 R connected to the positive terminal of battery B a lead is carried to spring 1 of jack J_3 . From spring 2 of jack J_1 connection is made to one terminal of the filament F of tube T_1 . In a similar manner connection 110

from spring 2 of jack J_2 is made to the filament of tube T_2 and a similar connection from spring 2 of jack J_3 to the filament F_2 of tube T_3 . The other filament terminals 5 are connected together as shown and to the negative side of the battery. Spring 3 of jack J_1 is connected to spring 2 of jack J_2 and spring 3 of jack J_2 is connected to spring 2 of jack J_3 .

10 As shown, spring 2 of each of the jacks J_1 and J_2 rests upon spring 3. It will now be seen that if the telephone plug is inserted in jack J_3 , springs 1 and 2 of jack J_3 will be forced into contact and a circuit may then 15 be traced from the positive terminal of battery B through the first section of resistance R to spring 1 of jack J_3 to spring 2 of the same to the filament F of tube T_3 , also, to spring 3 of jack J_2 , spring 2 of jack J_2 to 20 filament F of tube T_2 and also to spring 3 of jack J_1 , spring 2 of jack J_1 and filament F of tube T_1 .

If the telephone plug be withdrawn from J_3 and inserted in J_2 , the circuit formerly 25 closed by springs 1 and 2 will now be open and the circuit may be traced as follows: From the positive terminal of battery B through two sections of resistance R to spring 1 of jack J_2 , thence to spring 2 of 30 jack J_2 to filament F of tube T_2 , also, to spring 3 of jack J_1 , to spring 2 of jack J_1 to filament F of tube T_1 and thence to the battery.

If the telephone plug is withdrawn from 35 jack J_2 and inserted in J_1 , the circuit is opened through jacks J_2 and J_3 and may be traced as follows: From the positive terminal of battery B through the entire resistance R to spring 1 of jack J_1 , thence to 40 spring 2 of jack J_1 , thence through the filament F of tube T_1 and return. If the telephone plug is removed from jack J_1 all circuits are opened.

The number of sections into which the 45 resistance R should be divided and the value of each section may be easily ascertained as follows:

If the total number of tubes which it is 50 desired to use is x and the resistance necessary to be inserted in series with all of the tubes to insure proper voltage across the filaments of each is Y , then for any number 55 of tubes less than x desired to be used and designated by n , the proper value of resistance R to be applied is equal to R multi-

plied by $\frac{x}{n}$. For instance, if in the arrangement shown, all three tubes are in use and it is found that $2\frac{1}{3}$ ohms are necessary 60 to operate properly, then if only two tubes are to be used, the proper value of resistance is equal to $2\frac{1}{3} \times \frac{3}{2}$ or which is

equal to $3\frac{1}{2}$. If only one tube is to be used, the proper value of resistance is equal to $2\frac{1}{3} \times \frac{3}{1}$ or 7.

It is obvious that the arrangement is applicable to any number of tubes and with the disclosure which I have given, one skilled in the art may easily work out such an arrangement.

Having described my invention, what I claim is:

1. In radio signalling apparatus, having a plurality of vacuum tubes and each of said tubes having a cathode adapted to be heated, the combination of a source of energy for heating said cathode, a single resistance for controlling the current through all the cathodes jointly, means comprising a plurality of jacks, each associated with a tube for connecting an indicating instrument in the output circuit of said tube, and means associated with each of said jacks for energizing all of the tubes necessary for operation of said indicating instrument when inserted in any of said jacks at the proper voltage for said tubes.

2. In radio signalling apparatus, the combination of a plurality of vacuum tubes, each having a filament adapted to be heated, a source of energy for heating all of said filaments, a resistance in circuit with said source, a filament control jack associated with each of said tubes and connections from intermediate points of said resistance to each of said jacks respectively, said intermediate points being so chosen that the voltage drop through said resistance is substantially constant regardless of the number of tubes in use.

3. In radio signalling apparatus, the combination of a plurality of vacuum tubes, each having a filament adapted to be heated, a source of energy for heating all of said filaments, a resistance in circuit with said source, a filament control jack associated with each of said tubes and comprising means for lighting all of the tubes necessary for use, when a telephone plug or the like is inserted in any one of said jacks, and connections from intermediate points of said resistance to each of said jacks respectively, said intermediate points being so chosen that the value of resistance included in circuit with said source is always given by the

quantity $rx\frac{x}{n}$ where r is the resistance necessary to be included in series with said source to supply the proper filament voltage to one of said tubes alone, x is the total number of said tubes and n is the number of tubes in use at any given time.
